UNITED STATES PATENT OFFICE.

HENRY H. LEWIS, OF ATTLEBORO, MASSACHUSETTS.

BOX FOR CIGARETTES AND LIKE ARTICLES.

Application filed February 28, 1921. Serial No. 448,353.

To all whom it may concern:

Be it known that I, HENRY H. LEWIS, a citizen of the United States, residing at Attleboro, in the county of Bristol and State 5 of Massachusetts, have invented certain new and useful Improvements in Boxes for Cigarettes and like Articles, of which the following is a specification.

My invention relates to automatically operating containers for matches, cigarettes, and the like and is an improvement of my prior United States Patent No. 1,341,857 issued June 1, 1920.

The primary objects of my invention are 15 to prevent crushing the exposed ends of the contents when the cover is open; to provide a stop for the receptacle which will permit the same to be wholly detached from the casing or container and at will; to afford an effective locking means; to facilitate loading the receptacle; and to attain these objects in a simple and inexpensive structure.

My invention consists in the means and mechanism for producing the results above 25 specified substantially as hereinafter claimed.

In the accompanying drawings which form a part of this invention:

Figure 1 is a perspective view of my novel box closed,

30 Figure 2, a central transverse section of the same in open position, showing in broken lines the vibratory section partially closed,

Figure 3, a longitudinal sectional perspective view of the receptacle,

Figure 4, a perspective view of the receptacle wholly detached from the casing or shell, and

40 Figure 5, a fragmentary side elevation of the closed box partly in longitudinal section.

Similar reference numerals indicate like parts throughout the views.

As the construction is shown an open casing, container, or shell 6 comprises end walls 7, side wall 8, and a bottom 9. Fastened to the bottom is a leaf spring 10. Fastened by rivets 12 or otherwise at their lower ends to the walls 7 are vertical spring arms 13 having upon their upper ends inturned lips 14 below which are openings 15. Upon intermediate portions of the arms are operating lugs 16 extending through holes 17 in the walls 7.

55 A container or receptacle, slidably mounted in the casing, consists of a wall 19 com-

prising a body section 20 and a vibratory section 21. The former has a bottom or flange 22 provided with hinge sleeves 23, alternating with hinge sleeves 24 on a front plate or wall 25. Through both sets of sleeves passes a pintle 26 having one exposed end 27 laterally extended and engaging the bottom 22, while its other end is upwardly and inwardly bent forming a resilient finger 28 resting against the front face of the plate 25. Upon the ends of the section 20 are integral flanges or end walls 30 and 31. The latter is vertically extended above the section 20 forming a projection 32. The wall 30 has an opening 34 near its top, and to this wall is fixed by rivets 35 or otherwise the lower portion of a flat vertical resilient arm 37 projecting above the wall 30 to the same height as the portion 32 and provided with an intermediate opening 39 formed by cutting from the material a lateral upwardly inclined tongue 40 which projects through the opening 34 in the wall 30.

The sections 20 and 21 have cooperating hinge sleeves 42 and 43 respectively in which is a pintle rod 45 under torsional stress by having its ends fast in the end sleeves of the sections 20 and 21 in any usual convenient manner, whereby the section 21 is rearwardly impelled. Any other convenient spring means may be employed for this purpose. The section 21 has lateral flanges 47 and a top flange or extension 48. A cap or cover 49 on the flange 48 has hollow projecting end portions 50 in which are fixed depending fingers 52 having upon their ends beveled hooks or lugs 53. A cigarette 55 is shown held in the receptacle pressed by the plate 25.

The receptacle rests in the casing 6 upon the spring 10 by which it is upwardly pressed. This pressure is resisted, when the box is closed by the hooks 53 which are engaged in the openings 15 of the arms 13 which enter the casing between the end walls 7 and the arms. The receptacle is released by inwardly pressing the lugs 16. When thus released the receptacle rises until it is stopped by the contact of the tongue 40 with one of the lips 14 whereupon the released section 21 swings back to horizontal position as shown in Figures 2 and 4, and the end of the cigarette 55 or other contents of the receptacle project. In this position, if by negligence or otherwise, the section 21 be ac-

identally swung forward more than ninety degrees the cigarette would be broken, were it not that as soon as the section reaches a vertical position as shown in broken lines it is checked by contact with the projections 32 and 37.

The receptacle may be detached from the casing for reloading by manually pushing the extension 37 inwardly slightly just sufficient to clear the lip 14.

I claim:—

1. In a box of the character described, a casing provided with an opening, resilient arms fast to the sides of the casing provided with openings, a receptacle slidably mounted in the casing comprising a body section, a vibratory section pivotally connected with the body section and a spring for throwing the vibratory section to a position at an angle to the casing when ejected therefrom, resilient means for forcing the vibratory section through the opening, depending fingers upon the vibratory section, and heads upon the fingers adapted to register in the openings in the arms.
2. In a box of the character described, a casing provided with an opening, resilient arms fast to the sides of the casing, a receptacle slidably mounted in the casing comprising a body section, and a vibratory section pivotally connected with the body section, resilient means for forcing the vibratory section through the opening, a tongue supported by the body section, and a lip on one of the arms in the path of the tongue.
3. In a box of the character described, a casing provided with an opening, resilient arms fast to the casing, a receptacle slidably mounted in the casing comprising a body section, side walls on the body section, one of said walls being provided with a slot, and a vibratory section pivotally connected with the body section, resilient means for forcing the vibratory section through the opening, a resilient arm yieldingly mounted on said wall, a tongue on the last mentioned arm extending through the slot, and a lip on one of the first mentioned arms in the path of the tongue.
4. In a box of the character described, a

casing provided with an opening, resilient arms on the casing, a receptacle slidably mounted in the casing comprising a body section, side walls on the body section, and a vibratory section pivotally connected with the body section, resilient means for forcing the vibratory section through the opening, a tongue carried by one of the side walls, a lip on one of the arms in the path of the tongue, and vertical extensions on the side walls in the path of the vibratory section.

5. In a box of the character described, a casing provided with an opening, resilient arms in the casing, a receptacle slidably mounted in the casing comprising a body section, side walls, a bottom, a yielding clamping plate pivotally mounted at its lower end on the bottom and spaced from the body section, and a vibratory section pivotally mounted on the top of the body section, resilient means for forcing the vibratory section through the opening, a tongue supported by the body section adjacent the clamping plate, and a lip on one of the arms in the path of the tongue.

6. In a box of the character described, a casing provided with an opening, a receptacle slidably mounted in the casing comprising a body section, and a vibratory section adapted to be ejected therefrom, locking fingers on the vibratory section, a tongue supported by the body section, resilient means for forcing the vibratory section through the opening, and resilient means on the tongue detachably engaging the locking fingers.

7. In a box of the character described, a casing provided with an opening, resilient arms fast to the casing, a receptacle slidably mounted in the casing comprising a body section and a vibratory section adapted to be ejected therefrom, resilient means for forcing the vibratory section through the opening, and means carried by the vibratory section engageable with the arms locking the receptacle.

In testimony whereof I have affixed my signature.

HENRY H. LEWIS.
